Primary Examiner — Karen S Acker(74) *Attorney, Agent, or Firm* — Tallam I. Nguti, Esq.(57) **CLAIM**

The ornamental design for a digital user interface screen with software application icon, as shown and described.

DESCRIPTION

FIG. 1 is a front view of a digital user interface screen with software application icon in accordance with the present invention; and,

FIG. 2 is an enlarged front detail view of area 2 circumscribed within FIG. 1.

The broken lines in the drawings represent unclaimed environmental subject matter and form no part of the claimed design.

1 Claim, 2 Drawing SheetsFIG. 1

FIG. 2
